FINNED INSULATOR

Jean Henri Meier, Tarbes, France, assignor to Compagnie Generale d'Electro-Ceramique, Paris, Seine, France, a company of France

Filed Jan. 27, 1959, Ser. No. 789,356

Claims priority, application France Mar. 7, 1958
3 Claims. (Cl. 174—211)

The invention concerns improvements relating to self-cleaning high-tension insulators, that is to say, insulators which are automatically self-cleaned by rain water, having one or more fins or ribs disposed helically along a vertical cylinder.

In the French patent application, February 26, 1957, for "Finned Insulator," the applicants have proposed to improve the behaviour of such insulators under impulse voltages by providing the edge of the fin or rib with a flange projecting on both faces.

The present invention has for its object the improvement of the resistance of these insulators to tracking in a contaminated atmosphere.

To this end, according to the invention, one provides on the one face of the helical fin or on the one and the other face of this fin, a protuberance situated between the cylinder of the insulator and the free edge of the fin.

There may be more than one protuberance on the same face of the fin. It is advantageous for one of the protuberances to be at the edge of the fin, and the preferred combination is that in which the edge of the fin bears a protuberance on each face with at least one intermediate protuberance, because one then improves at the same time the behaviour under shock voltages of the behaviour in contaminated atmospheres.

The following description in conjunction with the accompanying drawings, given by way of non-limitative example, shows the different features of the invention and the way in which they are realised, all arrangements, as is clear from the text as well as the figures, lying within the scope of the present invention.

FIG. 1 is a view in elevation, partially sectioned, of one preferred embodiment of an insulator according to the invention.

FIG. 2 is a partial sectional view of a simplified embodiment.

In the embodiment according to FIG. 1, the insulator according to the invention is constituted basically by an insulating body 1 sealed at its extremities into two metallic caps 2; the insulating body is constituted by a cylindrical post 3 bearing a fin in the form of a helical rib 4. The fin 4 is provided at its extremity with a flange 5 projecting from the one and the other face of the fin as described in the patent application referred to above. Moreover, the fin is provided with swellings or protuberances 6 and 7 on the one and the other face.

Tests carried out on insulators of the "support" type so constituted and of general dimensions: 756 mm., diameter 180 mm. for insulator with helical fins, diameter 210 mm. for an insulator with fins of the usual type, subjected to cycles of contamination comprising, under normal service voltage, an exposure to a dusty atmosphere for two hours followed by an exposure to a saline mist for four hours under strictly defined conditions, have

2

shown that the insulator with stacked fins of the normal type withstood 10 cycles whilst the insulator with the helical fin improved as described with respect to FIG. 1 withstood 15 cycles before tracking.

FIG. 2 shows a simplified embodiment in which a single protuberance 6 is provided on the upper face of the fin between the post 3 of the insulator and the free edge of the fin.

This intermediate protuberance may also be provided on the lower face of the fin as at 7 in FIG. 1 or, again, such a protuberance may be provided on each face of the fin or the one or the other face or both may bear several intermediate protuberances, this latter disposition being equally applicable in the case where there is a terminal protuberance on the edge of the fin as at 5 in FIG. 1.

For reason of simplification the examples shown bear only one helical fin. It is however clear that the invention is equally applicable when the number of helical fins is greater than one.

Moreover, the invention is applicable whether the post of the insulator is solid or hollow, whether it transmits forces either in compression or tension or only serves as a protective envelope for electrical conductors without mechanical action, and whether the head of the fin is inclined to the longitudinal axis of the insulator or is perpendicular to its axis as is shown in FIGS. 1 and 2.

It is preferable as shown in FIG. 1 that the section of the fin in an axial view should be such that the line delimiting the space between the two faces of adjacent turns, $a-b-c-d, a'-b'-c'-d'$ possesses an axis of symmetry $O-O'$. In effect, it is then possible to manufacture the insulator by turning.

It is sufficient to turn a fresh cylinder of ceramic paste (that is to say, an unfired blank of a ceramic material) about its axis (the vertical axis of the insulator shown in FIG. 1) and to move along the length of the cylinder a turning tool having the profile $a-b-c-d, a'-b'-c'-d'$.

What is claimed is:

1. A self-washing insulator comprising an elongated body of dielectric material having a helical rib integral theron extending along the length of said body, the rib having an upper and a lower face and on at least one face thereof a protuberance projecting from said face, and said protuberance extending longitudinally along the length of the rib intermediate said insulator body and the peripheral edge of the rib and extending coaxially with said peripheral edge of the rib.

2. A self-washing insulator comprising an elongated body of dielectric material having a helical rib integral theron extending along the length of said body, the rib having an upper and a lower face and on at least one face thereof a single protuberance extending longitudinally along the length of the rib intermediate said insulator body and the peripheral edge of the rib, and outermost symmetrical protuberances along the peripheral edge of the rib, symmetrical with respect to the rib and forming a groove between one of said outermost protuberances and the intermediate protuberance.

3. A self-cleaning insulator comprising an elongated body of dielectric material having a helical rib integral theron extending along the length of said body, the rib having an upper and a lower face and on each of said faces a single protuberance extending longitudinally along

the length of the rib intermediate said insulator body and the peripheral edge of the rib, the rib having outermost protuberances along the peripheral edge thereof symmetrical with respect to the rib faces and forming grooves on said faces between the outermost protuberances and the intermediate protuberances, and said outermost and intermediate protuberances and said grooves being disposed coaxially, and the intermediate protuberances being disposed symmetrically on said faces.
